UNITED STATES PATENT OFFICE.

ELIJAH W. MCLENDON, OF MARTIN'S STATION, ALABAMA.

WHIFFLETREE-IRON.

SPECIFICATION forming part of Letters Patent No. 271,093, dated January 23, 1883.

Application filed August 14, 1882. (No model.)

To all whom it may concern:

Be it known that I, ELIJAH W. MCLENDON, of Martin's Station, in the county of Dallas and in the State of Alabama, have invented certain 5 new and useful Improvements in Whiffletrees and Irons; and I do hereby declare that the following is a full, clear, and exact description thereof, reference being had to the accompanying drawings, and to the letters of reference 10 marked thereon, making a part of this specification.

This invention relates to certain improvements in whiffletrees and irons; and it has for its objects to provide certain means whereby 15 the ferrule may be secured to the whiffletree, and also the central cuff, as more fully herein-after specified. These objects I attain by the means illustrated in the accompanying drawings, in which—

20 Figure 1 represents a side elevation of my improved whiffletree. Fig. 2 represents a sectional view taken on the line xx of Fig. 1. Fig. 3 represents a section on the line yy of Fig. 1. Fig. 4 represents a side elevation of a 25 modification of my invention. Fig. 5 represents a section on the line xx of Fig. 4. Fig. 6 represents a sectional view on the line yy of Fig. 4, and Fig. 7 represents a side elevation of a modification of the ferrule.

30 The letter A indicates the whiffletree, and B the ferrules. As shown in Fig. 1, the ferrules are constructed with grooves around the peripheries, into which are adapted to be shrunk

the links C, to which the hooks D are attached, the link serving to clamp the ferrule to its seat. 35 The cuff is split at E, as indicated in Figs. 1 and 2, so that it may be placed upon the whiffletree conveniently and secured thereon by the link. The link is held in place by the notch F and the bolts G, which pass through 40 the whiffletree and the cuff.

In the modification shown in Fig. 4 the ferrules are provided with lugs H, between which the hooks are pivoted, and the cuff is made in two pieces with a groove for the reception of 45 the link. In the modification shown in Fig. 7 the thimble is provided with a hook formed on or attached directly to it.

Having thus described my invention, what I claim, and desire to secure by Letters Patent, 50 is—

1. In combination with the whiffletree, the ferrules provided with grooves in their peripheries and with links adapted to be shrunk into the grooves, substantially as specified. 55

2. In combination with the cuff, the link adapted to be shrunk thereon, whereby the cuff is confined to its seat, substantially as specified.

In testimony whereof I affix my signature, in 60 presence of two witnesses, this 23d day of June, 1882.

ELIJAH W. MCLENDON.
